UNITED STATES PATENT OFFICE.

ARTHUR M. CHAMBERS, OF THORNCLIFFE, ENGLAND.

MEDICINAL VAPORIZER.

SPECIFICATION forming part of Letters Patent No. 611,560, dated September 27, 1898.

Application filed March 1, 1898. Serial No. 672,170. (No model.)

To all whom it may concern:

Be it known that I, ARTHUR MARSHALL CHAMBERS, a subject of the Queen of Great Britain, residing at Thorncliffe, in the county 5 of York, England, have invented certain new and useful Improvements in Medicinal Vap- orizers; and I do hereby declare the following to be a full, clear, and exact description of the invention, such as will enable others skilled 10 in the art to which it appertains to make and use the same.

My invention relates to improvements in vaporizers in which medicated liquids or other compounds are vaporized for service in cases 15 of asthma or like diseases or for disinfecting purposes; and the objects of my improve- ments are, first, to provide means by which the vaporization is continued regularly and uni- formly for long periods without attention, and, 20 second, to afford facilities for regulating and adjusting the speed of vaporization, so that it is more or less rapid, as may be desired, while the vaporizer is entirely self-contained and portable. I attain these objects by the de- 25 vices illustrated in the accompanying draw- ings, in which—

Figure 1 is a side view, and Fig. 2 a front view, of the vaporizer. Fig. 3 is vertical sec- 30 tion through the evaporating-dish, and Figs. 4 and 5 are a plan and side view, respectively, of the candle-holder.

Similar letters refer to similar parts through- out the several views.

a is the base, stamped up out of tin-plate or 35 other suitable material and having at its re- cessed center a circular opening to receive a corresponding holder *b*, (shown separately in Figs. 4 and 5,) having at one side a ring or 40 handle *c*, by which it can be readily lifted in or out of the opening in the base *a*, in which it fits.

The holder *b* receives the lower end of a candle *d*, of the kind well known and largely used as "pyramid night lights," which when 45 once lighted are capable of giving, without attention, a steady flame for many hours.

From the base *a* rises a vertical cylinder *e*, which surrounds the candle *d*, except on one side, at *f*, which is open for a sufficient height 50 to allow the introduction and removal of the holder *b* and candle *d*, and upon the cylinder

e is attached a handle *g*, by which the entire vaporizer can be carried about.

Around the upper part of the cylinder *e* are a series of openings in the form of vertical slits *i* above the opening *f* at its side.

h is a cylindrical case fitting freely around the inner cylinder *e* opposite the openings *i* and having a series of openings correspond- ing with those in the inner cylinder. The 60 outer case *h* can be turned by a stud or han- dle *k* backward and forward for a short dis- tance around the inner one *e*, so that the open- 65 ings can be entirely opened or more or less closed. The upper end of this cylinder *e* is open, and in it fits a dish or receptacle *l* for the medicinal or disinfecting material to be heated or vaporized. It is made in the shape of a hollow bowl, as shown in section in Fig. 3, a flange or rim *m* around its upper edge fitting 70 upon and being supported by the upper edge of the cylinder *e*.

The bowl *l*, of copper or other metal or ma- terial, is of such thickness, especially at the bottom, that the heat from the burning candle 75 *d* is only transmitted through it sufficiently readily to keep the contents at just the re- quired temperature to insure their slow and uniform vaporization.

The substance to be vaporized is placed in 80 the bowl *l*, and the holder *b*, having the lighted candle *d* fitted into it, is placed in the recess in the base *a*. The bowl is thus heated and kept hot, and the intensity of the heat can be 85 regulated and varied by adjustment of the perforated outer case *h*, by means of which more or less of the heated air is allowed to pass out through the perforations *i*.

The vaporizer is very simple, cheap, port- able, and easily used and is very effective for 90 the purposes required.

What I claim as my invention, and desire to secure by Letters Patent, is—

A vaporizer consisting of a base having a circular opening in its center for the recep- 95 tion of a lamp or candle holder, of a hollow cylindrical body portion, provided with a han- dle, open at its upper end to receive an evapo- rating-pan, and provided at its lower end with a vertical opening for the introduction of a 100 lamp or candle; an annular rib around the upper portion of said cylinder above said ver-

tical opening; a series of vertical slots cut in said cylinder above said annular rib, and a movable circular band, surrounding the upper portion of the said cylinder, resting on said 5 annular rib and provided with a series of vertical slots, adapted to register with the slots in the upper portion of the said cylinder, substantially as described.

In testimony whereof I have hereunto affixed my signature in presence of two witnesses.

A. M. CHAMBERS.
